UNITED STATES PATENT OFFICE.

CLEMENT ARTHUR WILD, OF OLDHAM, ENGLAND.

KNIFE-CLEANER.

1,024,541.

Specification of Letters Patent. Patented Apr. 30, 1912.

Application filed May 29, 1911, Serial No. 630,198. Renewed March 11, 1912. Serial No. 683,091.

To all whom it may concern:

Be it known that I, CLEMENT ARTHUR WILD, a subject of the Kingdom of Great Britain, and resident of 184 Coppice street, 5 Oldham, in the county of Lancaster, England, engineer, have invented certain new and useful Improvements in Knife-Cleaners, (for which I have applied for Letters Patent in England, No. 9,087, dated April 10 12, 1911,) and of which the following is a specification.

This invention has for its object improvements in knife cleaners and in particular to those in which the cleaning surfaces consist 15 of two disks covered with felt or other yielding material and will be readily understood by reference to the accompanying drawings upon which:—

Figure 1 is a front view of a knife cleaner 20 made in accordance with my invention. Fig. 2 is a side view of same. Fig. 3 is a section on line 1—2 but not showing the grip or stand. Fig. 4 is a section on line 3—4.

25 The casing A which is made of thin metal and in such a manner that it allows the polishing powder being fed into the machine at the center through a suitably formed hopper B which is secured to or formed in one with the disk C and is of sufficient diameter to inclose three slots c^1 , c^2 and c^3 30 in the disk C through which the emery or polishing powder is directed by a brush D or other equivalent which is secured on the shaft or spindle E and revolves with it causing the powder to pass through on to the 35 felt and lie in indentations c^4 made for that purpose in the disks and felt, and on to the flat portion of the same. It will be seen that the slots c^1 , c^2 and c^3 do not go through 40 the felt and disk F but only through the disk C.

I provide a spiral spring M which rests 45 against a boss formed on the disk C and the necessary pressure for keeping the disks

together is regulated by the nuts m^1 and washer m^2 which screw on the spindle E.

The blade of a knife is inserted in the mouthpiece H which is provided with a brush h^1 on each of its sides for removing the 50 powder from the blade when withdrawn, the mouthpiece is also provided with a guide or rest h^2 ; the blade passes between the disks C and F and in the case of a carving knife is allowed to go through a 55 slot J at the other side of the casing A. After the powder is fed into the hopper B a cap K is affixed which will prevent it from flying out when the cleaner is being used. To prevent the powder clogging or 60 accumulating on the edges of the disks and pads I provide scrapers N of felt or other suitable material secured at convenient parts inside the casing A which will sweep the edges every revolution of the disks. 65

Instead of securing the cleaner to a table or other base by means of a clamp P I may form an extension or foot plate on the bottom portion of the casing A and having screw holes by which it can be attached directly to a table or a suitable base. 70

What I claim is:—

In knife cleaners of the kind described the one disk having slots right through the same together with indentations on both 75 disks and pads, means for feeding the emery or polishing powder into the center of the said disks and pads, means for guiding the emery or polishing powder on to the flat portion of the said disks and pads and preventing the accumulation of the same in the feeding hopper substantially as herein described. 80

In witness whereof I have hereunto set my hand in the presence of two witnesses. 85

CLEMENT ARTHUR WILD.

Witnesses:

GEOFFREY ANDREWS,
LYDIA ANDREWS.
